(57) **CLAIM**

The ornamental design for a “USB flash drive,” as shown and described.

DESCRIPTION

FIG. 1 is a top, front, and right side perspective view of my new design for a USB flash drive;

FIG. 2 is a front view of the USB flash drive shown in FIG. 1;

FIG. 3 is a rear view of the USB flash drive shown in FIG. 1;

FIG. 4 is a right side view of the USB flash drive shown in FIG. 1;

FIG. 5 is a left side view of the USB flash drive shown in FIG. 1;

FIG. 6 is a top view of the USB flash drive shown in FIG. 1; and,

FIG. 7 is a bottom view of the USB flash drive shown in FIG. 1.

The dashed lines are for illustrative purposes only and form no part of my claimed design.
